CLAIM

The ornamental design for an apparatus for mechanically guiding a water vehicle that is being released or retrieved, as shown and described.

DESCRIPTION

FIG. 1 is a top perspective view of an apparatus for mechanically guiding a water vehicle that is being released or retrieved in accordance with an embodiment of the present invention;

FIG. 2 is a top plan view of the apparatus of FIG. 1;

FIG. 3 a right elevation view of the apparatus of FIG. 1;

FIG. 4 a left elevation view of the apparatus of FIG. 1;

FIG. 5 a front elevation view of the apparatus of FIG. 1;

FIG. 6 a rear elevation view of the apparatus of FIG. 1; and,

FIG. 7 is another perspective view of the apparatus of FIG. 1. The broken lines shown herein are for illustrative purposes and form no part of the claimed design.
